BOAT

Ernest L. Conway, 3116 E. 54th St., Kansas City, Mo.

Filed Apr. 19, 1960, Ser. No. 60,254

Term of patent 14 years

(Cl. D71—1)

FIG. 1

FIG. 2

FIG. 3

FIG. 1 is a side elevational view of a boat, showing my design,

FIG. 2 is a top plan view thereof, and

FIG. 3 is a front elevational view thereof.

The side not shown is substantially the same in appearance as that shown in FIG. 1 and the bottom of the boat is plain.

The characteristic feature of my boat design resides in the particular seat support members associated with the seat and steering members, all as shown.

I claim:

The ornamental design for a boat, as shown and described.
